East Orange, N. J.

Application May 19, 1938, Serial No. 208,781

6 Claims. (Cl. 242—139)

This invention relates to kits and particularly to a sewing kit, an object being to provide a simple construction wherein a number of article-carrying spools are held in desired positions so that the thread and yarn therefrom may be readily removed without tangling.

Another object of the invention is to provide a kit carrying a comparatively large number of spools of thread and yarn which may be readily removed and which are so arranged that the thread or yarn is guided as it moves from the spools.

An additional object, more specifically, is to provide a kit adapted to support a number of spools of thread and yarn and in addition present means for receiving the various articles used in connection with thread or yarn.

In the accompanying drawings—

Fig. 1 is a side view of a kit disclosing an embodiment of the invention, certain spools of thread and yarn being shown in connection therewith;

Fig. 2 is a top plan view of the structure shown in Fig. 1;

Fig. 3 is an end view of the structure shown in Fig. 1;

Fig. 4 is a perspective view of one of the spool-carrying posts shown in Fig. 1;

Fig. 5 is a detail fragmentary perspective view of one of the feet shown in Fig. 1 and illustrating means for receiving the post shown in Fig. 4;

Fig. 6 is an enlarged fragmentary side view of one end of the supporting bars shown in Fig. 2, certain parts being broken away for better illustrating the construction of the thread guide 35 and holder;

Fig. 7 is a sectional view through Fig. 6 approximately on the line 7—7;

Fig. 8 is a longitudinal sectional view through Fig. 6 approximately on the line 8—8;

Fig. 9 is a detail fragmentary sectional view through Fig. 2 on the line 9—9.

Referring to the accompanying drawings by numerals, 1 indicates a body which is formed with supporting plates 2 and 3. Each of these plates is provided with an inclined lower portion, as shown in Fig. 1, and a vertical portion merging into the respective inturned covering flanges 4 and 5 which extend from one side of the kit to the needle-and-thread cushion 6. The flanges 4 and 5 are cut off so as to present small inturned gripping flanges 7 and 8, as shown in Fig. 9, at the part adjacent the cushion 6 whereby the small or reduced gripping flanges may be embedded slightly in the cushion for holding the same in place. This cushion may be felt or other material and is adapted to be forced downwardly into the position shown in Figs. 2 and 9. The flanges 4 and 5 are cut away at 9 to provide an opening for receiving a pair of scissors, while ad-

jacent the end of these flanges are provided pressed-up loops 10 and 11 which are similar to the loops 12 and 13 on the respective feet 14 and 15. These loops are shown particularly in detail in Fig. 5 and in this figure there are also disclosed pressed-up portions 16 and 17 so as to provide even support for the respective spools 18 and 19. In Fig. 4 there is disclosed a resilient post 20 preferably formed from a loop of flat spring metal. This loop merges into feet sections 21 and 22 which are inserted beneath the loops 10 and 11 when the thimble post 23 is provided. As indicated in dotted lines in Fig. 1, a thimble 24 is removably mounted on the post 23. The remaining posts are mounted to support the spools 18 and 19 or spools 25 and 26. All the posts are of identical construction and so are their fastening means. The construction shown in Fig. 5, therefore, will apply to each of the posts carrying the respective spools whether the spools are vertical or horizontal.

It will be seen from Fig. 2 that there is a row of spools on each of the feet 14 and 15. These feet are horizontal extensions of supporting plates 2 and 3, which plates are preferably reinforced by suitable bracing flanges 27 and 28. The respective side edges of the plates 2 and 3 at the upper portion are provided with a number of bendable tongues 29 which extend through suitable apertures 30 in the respective side plates 31 and 32, as illustrated particularly in Figs. 1 and 2. These side plates, generally speaking, are diamond-shaped, as illustrated in Fig. 1, so that from the side they will substantially cover the spools 25 and 26 and, at the same time, present a desired bracing structure for the plates 2 and 3. At the outer ends the respective side plates are provided with suitable supporting bars 33 and 34 together with their respective closure plates 35, as shown in Fig. 7. As the structures of the respective devices are identical a description of one will apply to both.

As shown in Figs. 6 to 8 inclusive, the supporting plate 33 is U-shaped in cross section and at spaced intervals is provided with notches 36 at the top and bottom so as to receive the respective guides and holders 37. The supporting bar 33 and the closure plate 35 are held in place by being connected with the side plates 31 and 32, as illustrated in Fig. 8. It will be observed that bendable prongs 38 and 39 extend through suitable apertures in the side plates 31 and 32 and are bent over to lock the parts in place. The prongs or tongues 39 are substantially U-shaped in cross section so as to provide a brace to prevent collapsing of the outer ends of the plates 31 and 32 as well as prevent spreading thereof. Each of the guides and holders 37 is formed as shown in Fig. 6 wherein there are provided slots or notches 40 and 41 arranged diagonally. It will

be noted that the upper part of the guide and holder 37 is wider than the lower part and slidably fits into the slot 36', while the lower part 42 slidably fits into the slot 36. Also it will be noted that there are provided laterally extending wings or abutments 43 and 44 which will prevent the members 37 from moving out of the supporting bar 33. However, these members may freely move upwardly and downwardly when it is desired to insert a thread into either of the slots 40 or 41. The upper end of the guide 37 is pulled upwardly until the abutments 43 and 44 strike the upper part of the supporting bar 33. This will expose the lower ends of the respective slots 40 and 41 so that a new thread may be easily inserted. These slots are preferably very narrow but are sufficiently wide to allow the thread or yarn to slide therethrough. Preferably the parts are so proportioned that the guide and holder 37 will rest on the thread, as shown in Fig. 6, whereby a certain tension is presented. When a thread or yarn is pulled the holder 37 will slide upwardly a short distance to allow the free movement of the thread.

From Figs. 1 and 2 it will be seen that the various spools 18 and 26 carry darning yarns while the remaining spools carry sewing threads. While this is a desired arrangement other arrangements of the spools may be made without in any way departing from the spirit of the invention. However, it is thought preferable to have the spools 18 and 25, which are in alignment, used in connection with the same guide and holder 37. For instance, expressed in another way, the thread or yarn from these spools extend through the respective slots 40 and 41 of the holder 37 nearest these spools.

It will be seen that the yarn passes substantially in a horizontal direction from the upper spool 40 and substantially in a vertical direction from the lower spool. Also it will be observed from Figs. 1 and 7 that the bars 33 and 34 are arranged at an angle so that the lower portion of extension 42 of the respective members 37 will not interfere with the yarn passing upwardly and over the bar 33 or 34 as the case may be. It will also be noted that the various posts 28 resiliently engage the respective spools so as to yieldingly hold the spools in place. This resilient action is intended to be sufficient to prevent any of the spools rotating and, consequently, the parts are so arranged that the yarns and thread will feed from the end of the respective spools.

After one or more of the threads or yarns have been pulled the desired distance the same may be cut off by the scissors or broken in any desired manner. It will be observed that the threads and yarns will not become tangled while the supply thereof is being pulled from the kit and that each thread and each yarn is always ready to be pulled so that a workman may readily receive any desired quantity of thread or yarn.

We claim:

1. A sewing kit comprising a body, means carried by the body for supporting a straight row of thread- and yarn-carrying spools in a horizontal plane, the axes of said spools being in a horizontal plane and arranged in parallelism, a plurality of means for carrying a straight row of 70 of thread- and yarn-carrying spools in vertical planes, the axes of said spools being in vertical planes and arranged in parallelism, and a row of guides for the thread and yarn, said guides being so arranged that the thread or yarn from 75 a vertically-extending spool and from a hori-

zontally-extending spool will pass therethrough, said guides being arranged substantially in axial alignment with the spools from which the thread and yarn come.

2. A sewing kit provided with a body having diagonally-arranged lower sections merging into a pair of parallel vertical sections, each of said lower sections having a horizontal foot, a pair of side members, means for securing the side members to said vertical sections, a row of vertically-extending spool-carrying posts carried by each of said feet, a row of horizontally-extending spool-carrying posts carried by each of said upper sections, said posts on the upper section extending in opposite directions, and means carried by said side members substantially axially disposed in respect to the posts on said feet and the posts on said vertical sections for guiding thread and yarn from the respective spools over the ends of the spools carried by the respective posts.

3. A sewing kit comprising a body, means on the body for carrying a row of horizontally-extending spools with their axes in parallelism, means for carrying a row of vertically-extending spools with their axes in parallelism, said rows of spools being arranged so that there will be a horizontally extending spool in the vertical plane of each vertically extending spool, and an independent thread and yarn guide for each of the spools in each of said vertical planes.

4. A sewing kit comprising a body formed of sheet metal and provided with a lower structure and an upper structure, a plurality of vertically extending posts carried by said lower structure, said posts being arranged in a pair of rows, and a pair of rows of spool-carrying posts supported by said upper section and arranged to support spools in a horizontal plane, all of said posts being arranged so that one lower post and one upper 40 post on each side of the body will be in the same vertical plane, and a thread guide and holder arranged in each of said vertical planes and provided with two guideways so as to accommodate the thread from one vertically arranged spool 45 and one horizontally arranged spool.

5. A sewing kit of the character described including means for supporting a plurality of spools so that they will not rotate, guiding structures for guiding the thread from said spools, each of 50 said guiding structures including a substantially vertically reciprocating guide and holder formed with a pair of diagonally arranged thread-receiving slots open at one end and a pair of supporting shoulders and a supporting structure in which 55 said guide and holder is slidably mounted, said supporting structure being provided with means on which said shoulders are adapted to rest when the holder is in its lowered position.

6. A sewing kit including means for supporting 60 a plurality of thread-carrying spools and guiding structures for the thread on said spools, said guiding structures including a supporting bar substantially U-shaped in cross section provided with upper and lower openings, a thread guide 65 and holder arranged adjacent each of said spools, said guide and holder being flat and slidably mounted in said openings, said guide and holder being provided with a pair of diagonally arranged slots for receiving the threads, and a pair 70 of abutments for preventing accidental removal from said supporting U-shaped bar.
